UNITED STATES PATENT OFFICE.

THOMAS CLARKSON AND WILLIAM JOHN MORISON, OF CHELMSFORD, ENGLAND.

REGULATOR FOR LIQUID-FUEL BURNERS.

No. 870,083.

Specification of Letters Patent.

Patented Nov. 5, 1907.

Application filed January 2, 1906. Serial No. 294,228.

To all whom it may concern:

Be it known that we, THOMAS CLARKSON and WILLIAM JOHN MORISON, both subjects of the King of England, residing at Chelmsford, Essex, England, have invented certain new and useful Improvements in Regulators for Liquid-Fuel Burners, of which the following is a specification.

This invention relates to regulators for liquid fuel burners and has for its object to construct a device that shall be prompt and certain in its action particularly when used in conjunction with a steam generator heated by a burner of this type.

According to this invention the movement necessary to control the burner is obtained by the co-operation or the combined effect of temperature and pressure of the content of the generator. The means by which the desired end is accomplished are such that the temperature and pressure co-operate to effect the complete control necessary with a steam generator wherein the fluctuations of temperature and pressure are such that both rapid and steady action on the part of the regulator are necessary to effect corresponding regulation in the supply of heat to the generator.

According to one construction of this invention, a single expandible tube is disposed across the bottom of the generator above the burner, the tube being carried in such a way that the heat will not distort its supporting frame. One end of the tube is connected to a hollow stationary support and at its free end the tube carries a pin which rests against the lever or other mechanism whose movement is imparted to the means for controlling the burner. The lever is conveniently provided with two arms, one of which is engaged by the pin already mentioned, the other being in engagement with a second pin. This pin is connected to a spring controlled piston which is adapted to move in a chamber to which the contents of the generator have access. The pressure within the generator acts on the piston to force its pin outwards and operate one arm of the lever and the expansion of the tube under the influence of the temperature of the generator contents also acts to operate the other arm of the lever, the control of the burner being thus obtained by the combined effect of temperature and pressure of the generator contents.

The amount of expansion of the straight tube may be increased in the following way:—A straight tube of convenient length and formed of suitable metal having a moderate coefficient of expansion has one end secured in the union to which the inlet steam pipe is attached. This end of the tube is therefore relatively fixed. A second tube of nearly the same length is passed over the first tube, this second tube being formed of some metal or alloy having a coefficient of expansion so low as to be practically negligible. The free end of the first tube is rigidly connected to the corresponding end of the second tube. Over these two tubes is passed a

third tube formed of the same metal as is used for the construction of the first tube, and what may be termed the inner end of this third tube is secured to the corresponding and free end of the inexpandible tube. The steam is taken off from the outer end of the third tube which also carries the pin actuating the control mechanism. The telescopic arrangement of the three tubes is such that the effect of a single long tube of expandible metal is obtained.

The construction of the regulator may vary considerably in accordance with the purposes for which it is to be used and the types of generator and burner with which it is to be combined.

Referring to the drawings:—Figure 1 is a sectional view of a construction employing three tubular members arranged concentrically. Fig. 2 is an elevation partly in section of a modification.

Like letters indicate like parts throughout the drawings.

The tube A is surrounded by a tube A⁶ having conveniently the same coefficient of expansion and between these tubes is disposed another tube A⁸, the coefficient of expansion of which is negligible. This tube A⁸ is joined at its corresponding end to the free end of the tube A and at its opposite end to the neighboring end of the tube A⁶. In this manner a telescopic tube is provided. At its other end the tube A⁶ has screwed to it a box A² to which the steam outlet pipe A⁵ is connected. The steam enters the box which supports the tube A through a pipe A⁴ and after passing through the tube is withdrawn by the pipe A⁵. On the end of the cap A² is the pin C the body of which is formed integral with the cap, as shown, the pin being provided with an adjustable head, and used in conjunction with a control device such as will be described with reference to Fig. 2 to operate the burner.

Referring now to Fig. 2, a single expandible tube A is connected at one end to a hollow stationary support A² and at its free end carries the pin C sliding in a bearing in the bracket D. The lever E in this case is provided with two arms E¹ E² of which the arm E¹ is pressed against by the pin C, while the arm E² projects downward and is engaged by a pin C¹. This pin C¹ is connected to a piston C² adapted to move in a chamber C⁴ and the chamber communicates by a pipe G with the contents of the generator. The pressure within the generator, therefore, acts on the rear end of the piston against the action of a spring C³ to force the pin outward and operate the lever E. The lever can thus be operated by the expansion of the tube A under the influence of the temperature of the generator contents and by the pressure within the generator acting upon the piston C². Conveniently the generator contents are conveyed to the free end of the tube by a stationary tube A⁵ and after passing along said tube about an inner tube A⁶ which extends to within a short distance

of the closed end of the tube A, escape through said inner pipe A⁸ which projects through the open end of the tube A.

The wire A⁹ may be wound spirally between the 5 tubes to preserve concentricity between the tubes and to insure uniform heating of the outer tube by a spiral distribution of the steam, thus heating both sides equally.

When the spring-controlled piston device is employed, the construction is conveniently such that this device does not come into action during ordinary working, that is to say, when the steam generated is being used, the control of the burner being effected by the member operated by the temperature. When 10 steam is shut off the consequent rise of pressure brings the pressure device into operation to shut down the burner or furnace. The prearranged pressure at which the pressure device comes into operation can be determined by regulating the power of the spring therein.

20 What we claim as our invention and desire to secure by Letters Patent is:-

1. In a regulating device for a liquid fuel burner, the combination with a rocking bell-crank lever and an operative connection between one arm of the lever and the burner-regulating device, of a tubular expansible member 25 to which the contents of the generator heated by the burner have access, a fixed bearing for one end of the tube, a support for the other end of the tube, means whereby the contents of the generator have access to the tube, means for transmitting movement due to the expansion of said tube to the bell-crank lever, a casing, a movable member in the casing, means whereby the pressure of the generator contents has access to the movable member, and means whereby the movable member acts upon the bell-crank lever.

30 2. In a regulating device for a liquid fuel burner, the combination with a rocking bell-crank lever, and an operative connection between one arm of the lever and the burner-regulating device, of a tubular expansible member 35 to which the contents of the generator heated by the burner have access, a fixed bearing for one end of the tube, a bearing for the other end of the tube in which it

can slide, means whereby the contents of the generator have access to the tube, means for transmitting movement from said tube to the bell crank lever, a casing, a movable 45 member in the casing, means whereby the pressure of the generator contents has access to the movable member, and means whereby the movable member acts upon the bell-crank lever.

3. In a regulating device for a liquid fuel burner, the 50 combination with a lever, a rocking shaft carrying the lever, and an operative connection between the lever and the burner-regulating device, of an expansible tubular member closed at one end, a fixed hollow bearing for the open end of the tube, a projection on the closed end of the tube, 55 a bearing in which the projection can slide, an arm fixed to the rocking shaft and adapted to be contacted by the projection, a second projection on the rocking shaft, a piston, a cylinder in which the piston works, a connection between the cylinder and the interior of the generator, a rod connected to the piston and adapted to contact with the second projection on the rocking shaft, and a spring bearing 60 against one side of the piston.

4. In a regulating device for a liquid fuel burner, the 65 combination with a lever, a rocking shaft carrying the lever, and an operative connection between the lever and the burner-regulating device, of an expansible tubular member closed at one end, a fixed hollow bearing for the open end of the tube, a pipe leading into the hollow bearing, a projection on the closed end of the tube, a bearing 70 in which the projection can slide, a tube leading through the hollow bearing to the inner end of the expansible member, circulating devices between the tubes, an arm fixed to the rocking shaft and adapted to be contacted by the projection on the closed end of the expansible tube, a 75 second projection on the rocking shaft, a piston, a cylinder in which the piston works, a tubular connection between the cylinder and the interior of the generator, a rod connected to the piston and adapted to contact with the second projection on the rocking shaft, and a spring bearing 80 against one side of the piston.

In testimony whereof we have signed our names to this specification in the presence of two subscribing witnesses.
